United States Patent Office

Des. 228,364
Patented Sept. 11, 1973

228,364

LABEL PRINTING TOOL

James H. Lee, Walnut Creek, Calif., assignor to Dymo
Industries, Inc., Emeryville, Calif.

Filed June 11, 1970, Ser. No. 23,443

Term of patent 14 years

Int. Cl. D18—99

U.S. Cl. D64—10

FIG. 1 is a perspective view of a label printing tool showing my new design;

FIG. 2 is a side elevational view thereof, illustrating the side of the tool not disclosed in FIG. 1;

FIG. 3 is a bottom plan view; and

FIG. 4 is a rear elevational view.

I claim:

The ornamental design for a label printing tool, substantially as shown.
